NAPHTHA AIR SWEETENING

George W. Ostberg, Roselle Park, N.J., assignor to Esso Research and Engineering Company, a corporation of Delaware

Application June 13, 1955, Serial No. 514,993

8 Claims. (Cl. 137—592)

The present invention relates to a process and apparatus for sweetening naphtha compositions. More specifically, in accordance with the present invention sour gasoline stocks are sweetened by contact with air in a storage tank equipped with baffling means whereby maximum residence time of control between incoming air and naphtha is realized to produce a completely air sweetened naphtha.

The removal of undesired sulfur compounds from petroleum products is a perennial problem in the petroleum refining industry. While there have been many suggestions made as to processes for removing undesired sulfur compounds, the desire for simplified sulfur removal processes remains. Again new problems are encountered in the processing of novel feed stocks or unusual blends of stocks.

Comparatively recently it has been discovered that certain stocks are susceptible to what is known as air sweetening. For example, certain gasolines during simple storage under conditions to expose the gasolines to oxygen will undergo a process in which mercaptans are converted to disulfides. This conversion of sulfur compounds from mercaptans to disulfides is called "sweetening" by virtue of the fact that the disulfides, unlike the mercaptans, are not malodorous. The basic simplicity of the air sweetening process holds great promise as a finishing procedure for stocks susceptible to this treatment in order to provide the last incremental improvement in sweetening which is often required. The present invention is concerned with an improvement in air sweetening techniques providing for increased rates of sweetening of those stocks which respond to air sweetening. It is a particular feature of the process that it has been found to be of particular application to the sweetening of blends of cracked gasolines with virgin gasolines, since virgin gasolines are normally unresponsive to air sweetening.

In commercial installations, sour naphtha is generally sweetened in storage tanks under conditions to obtain the necessary residence time to convert mercaptans to disulfides. This residence time, of the order of 24 to 96 hours, depending upon the characteristics of the crude, has been obtained by passing air-treated naphtha from a mixing zone to a storage tank equipped with two inlet nozzles. One nozzle is located at ground level and the second about 10 feet above the lower nozzle. When the tank is empty or nearly so, the lower inlet nozzle is used for filling. The naphtha is passed in at production rate, i.e., the rate at which it is produced at the processing unit. When the naphtha level reaches the upper nozzle, the lower connection is shut off and the upper one is opened. This allows the incoming naphtha, which is usually warmer than the naphtha in tankage, to remain as the top stratum of the naphtha. Since the naphtha is withdrawn through a nozzle or port, also situated at ground level, the naphtha that is withdrawn from the bottom is that which has remained in the tank for the longest period.

The arrangement described has been found not to be completely satisfactory. In the first place, it requires

2

constant operating attention to insure proper closure and opening of valves, depending upon the level of the air-treated naphtha within the tank. Also, there is a potential safety hazard of naphtha discharging through the elevated nozzle above the liquid level of the naphtha. Furthermore, when the level of the naphtha is appreciably above the top nozzle, maximum residence time is not attained as the horizontally entering naphtha mixes and circulates with naphtha partially aged in the tanks.

It is, therefore, the principal object of the present invention to set forth a naphtha sweetening tank specifically adapted to overcome the above mentioned disadvantages in commercial installations.

It is a further purpose and object of the present invention to set forth a tank arrangement affording a maximum of residence time, elimination of operating attention, and elimination of a potential safety hazard.

Other and further objects and advantages of the present invention will become apparent hereinafter.

In accordance with the present invention the second or upper nozzle of the tank is replaced by a suitable baffle such as a plate or box baffle. The baffle is installed with sufficient clearance from the tank floor so that with normal flow input, the level within the baffled section is about 3 to 6 inches higher than the level on the storage side. The baffle extends upward for approximately one third to one half of the height of the tank. When the naphtha level in tankage reaches the top of the baffle 95-100% of the flow is upward, and the remainder is through the underclearance to the bottom portion of the tank. This division is affected by both the warmer temperature of the incoming naphtha and the higher resistance to flow underneath the baffle. Consequently, the incoming naphtha is diverted vertically to the top of the naphtha volume, and maximum residence time for the sweetening and aging is obtained.

The present invention will be more clearly understood when read in conjunction with the drawings which represent schematically preferred embodiments thereof.

40 In the drawings:

Figure I is a schematic diagram of a process for sweetening sour naphtha.

Figure Ia is a partial top sectional view of naphtha storage tank 20 of Figure I.

Figure Ib is a partial top sectional view of a modification of the storage tank shown in Figure Ia.

Figure II is a partial side sectional view of a naphtha storage tank wherein the baffle is pipe 30.

Figure III is a plan view of the storage tank in Figure II with the interior baffle shown in dotted lines.

Figure IV is a partial side sectional view of a modification of the storage tank shown in Figures II and III.

Turning now to Figure I, the sour naphtha is preferably given a preliminary caustic wash in vessel 2 to remove hydrogen sulfide, which would be converted to free sulfur in the subsequent air treating step. The naphthas to be sweetened by this process may be identified by reference to the mercaptan content of the stock. As indicated by the copper number of the gasoline, the sweetening process is particularly applicable to those gasolines, having a copper number ranging from about 1 or less, to 15. As will be understood, such gasolines may also constitute gasolines obtained from prior sweetening operations or from relatively low sulfur crude oils, and particularly from gasolines derived from thermal or catalytic cracking operations.

Caustic soda employed for the caustic wash may be introduced through line 4 for mixture with the sour naphtha in vessel 2, which may be an orifice mixer. About 1-10 volumes of 5-30% caustic may be employed.

It has also been found desirable to add an antioxidant inhibitor to the naphtha prior to or during the subsequent

air-sweetening process. Of particular effectiveness are the phenylene diamines, in particular, the *N,N'*-di-alkyl *p*-phenylenediamines. These inhibitors may be added to the gasoline preferably after the caustic washing, to the extent of from about 0.1-2 lbs. per 5,000 gallons of naphtha.

The sour naphtha, after admixture with caustic, is withdrawn from vessel 2 through line 6 and, after addition of inhibitor through line 10, is brought to settling zone 12, and spent soda withdrawn through line 14. The naphtha washing operation is carried out preferably in the absence of air.

The caustic-washed naphtha is then passed to an air-mixing zone 16. Air may be introduced through line 18 by means of a compressed air line or the like. The air injected should not be less than about 0.05 standard cubic foot per copper number per barrel of naphtha treated. Thus for a gasoline of 10 copper number, 0.50 s.c.f. of air per barrel is about the minimum requirement, but about 1.5 s.c.f. is preferred to speed up the sweetening rate.

The process is preferably operated continuously, but throughput must be controlled so that the hold-up time in zone 20 is sufficient to complete sweetening.

In accordance with the present invention, the naphtha admixed with air is conducted to baffled storage vessel 20. This vessel is a conventional storage tank adapted for storing volatile and inflammable hydrocarbons but, in accordance with the present invention, also equipped with baffle 22. The vessel is of sufficient size for 4 days' production hold-up, for example 40' diameter by 36' height. Baffle 22 may be of plate (Figure 1a) or box (Figure 1b) design and its lower portion affords a clearance or underpass of about 5 to 10 square inches, that is, the baffle is installed with sufficient clearance from the tank floor so that with normal flow input of 1600-4000 barrels per stream day, the level within the baffle section is 3-6 inches higher than the level on the storage side. The baffle extends upwardly approximately one half the height of the tank. In one embodiment, it is welded to the tank wall.

The air-mixed naphtha is passed into tank 20 through line 24 and nozzle 26. As indicated previously, initially the level within the baffled section is some 3-6 inches higher than the level on the storage side, the naphtha passing under the baffle. At this stage, it is generally not desirable to withdraw naphtha from outlet nozzle 28, due to incomplete ageing. When the naphtha level in the tankage reaches the top of baffle 22, 95-100% of the flow is upward and the remainder through the under-clearance in the bottom portion of the tank. This results in part from the warmer temperature of the incoming naphtha which may be 70° to 100° F. while the bottom portion approaches ambient temperature, say 50 to 80° F., and also by the higher resistance to flow underneath the baffle. Thus the incoming naphtha is diverted vertically to the top of the naphtha volume and the maximum residence time for ageing is obtained. The tank may be filled to a level substantially above the top of the baffle without loss of effective residence time.

After a hold-up period of 24 to 96 hours, the aged product, now fully air-sweetened, is withdrawn from tanks 20 through outlet nozzle 28 and is further processed in a manner not forming a part of the present invention. Thus, it may be water-washed if desired, or passed directly to storage. Similarly, tank 20 may be further provided with vents and outlets to withdraw air separated from the naphtha.

Though the process and construction of the present invention find their immediate utility in the air sweetening of naphtha, it is evident that they find utility in other applications where a maximum of residence time of a liquid in a tank, for aging or other effect, is desired. The advantages of the present invention over present installations and processes include the elimination of

operating attention to the tank in that there are no valves to open or close, depending upon the level within the tank; the elimination of the potential safety hazard of naphtha discharging through an elevated nozzle above the liquid level of the naphtha; and the full effectiveness of the baffle installation at all levels above the top of the baffle. In prior arrangements, maximum residence time could not be realized when the naphtha level was appreciably above the top nozzle.

Another embodiment of the present invention is shown in Figure II. The baffling effect is provided by a vertical pipe 30 coupled to the tank inlet nozzle 32. Pipe 30 is about 10-20 feet in length and 12-16 inches in diameter, and the corresponding nozzle may be 4-6 inches in diameter. Opposite the inlet nozzle in pipe 30 is slot 34, having an area of 5-10 square inches, providing for bottom flow of naphtha into the tank, as in the case of the baffle previously described. If desired, a swing or other type check valve may be used instead of bottom slot or orifice 34. Such arrangement is shown in Figure IV.

In a typical tank employing this alternate pipe 30 may be installed in a naphtha storage tank 40 feet in diameter and 36 feet high. Standpipe 30 is 12 inches in diameter and stands 15 feet high. Slot 34 measures 1 inch by 5 inches, and the differential head through slot 34 is about 4 inches. The naphtha flows upwardly through standpipe 30 and passes into the tank through its upper openings 36. The relationship of standpipe 30 to tank 20 is clearly seen in Figure III.

The standpipe arrangement has the advantage of minimizing welding in the tank, cheaper and simpler construction, and easier installation. The 12" pipe with a 4" connection may readily be carried into a tank of say 40' diameter and 36' height through the standard 24" manhole. The larger size standpipe, say 16" size with 6" connection is used for larger tanks handling large naphtha rates, and can be entered through the standard 28" manhead on these tanks.

What is claimed is:

1. In a naphtha storage tank in combination a tank, conduit inlet means in the lower portion of said tank adapted to conduct vaporizable liquids into said tank, a vertical baffle attached to the side wall of said tank to form a flow space between said baffle and said side wall which communicates with said inlet means, said baffle being positioned above the floor of said tank and extending upwardly $\frac{1}{3}$ to $\frac{1}{2}$ the height of said tank, said baffle additionally being positioned close to said inlet means and extending downwardly to form with the floor of said tank an opening having substantially smaller cross section than said inlet means, and conduit means in the lower portion of said tank adapted to withdraw said liquid, said last named conduit means being further removed from said baffle than said conduit inlet means.
2. The apparatus of claim 1 wherein said baffle is a plate baffle.
3. The apparatus of claim 1 wherein said baffle is a box baffle.
4. The apparatus of claim 1 wherein said inlet means is a nozzle.
5. In a naphtha storage tank in combination a tank, conduit inlet means in the lower portion of said tank adapted to conduct vaporizable liquids, a vertical pipe positioned on the floor of said tank and in communication with said inlet means, said pipe extending for a distance of about $\frac{1}{3}$ - $\frac{1}{2}$ the height of said tank and the upper portion of said pipe being in open communication with said tank, outlet means in the lower portion of said pipe, said outlet means being of substantially smaller cross section than said inlet means, and conduit means in the lower portion of said tank adapted to withdraw said liquid, said last-named means being substantially further removed from said pipe than said inlet means.
6. The apparatus of claim 5 wherein said outlet means from said pipe is substantially opposite said inlet means.

7. The apparatus of claim 5 wherein said lower outlet means from said pipe is a swing check valve.

8. The apparatus of claim 5 wherein said pipe has a support means disposed above said inlet means.
